United States Patent Office

Des. 191,352
Patented Sept. 19, 1961

191,352

DISPENSER FOR TRAYS, SILVERWARE, AND NAPKINS OR THE LIKE

Philip Golden, Teaneck, N.J., assignor to S. Blickman, Inc., Weehawken, N.J., a corporation of New York

Filed Dec. 1, 1960, Ser. No. 63,059

Term of patent 7 years

(Cl. D14—3)

FIG. 1

FIG. 2

FIG. 4

FIG. 1 is a front perspective view of a dispenser for trays, silverware, and napkins or the like embodying my new design,

FIG. 2 is a left side elevational view,

FIG. 3 is a front elevational view, and

FIG. 4 is a top plan view thereof.

The side not shown is a mirror image of the side shown and the rear is substantially plain.

I claim:

The ornamental design for a dispenser for trays, silverware, and napkins or the like, substantially as shown and described.
